UNITED STATES PATENT OFFICE

CLARENCE E. MILLER, OF CANTON, NORTH CAROLINA, ASSIGNOR TO THE CHAMPION FIBRE COMPANY, OF CANTON, NORTH CAROLINA, A CORPORATION OF OHIO

DEHYDRATING CAUSTIC ALKALI SOLUTIONS

No Drawing.

Application filed August 19, 1931. Serial No. 558,187.

This invention relates to the evaporation of solutions which absorb, or whose solid content reacts chemically with carbon dioxide, carbon monoxide or other constituents of the 5 gaseous combustion products from the commonly-used solid, liquid or gaseous fuels. The invention is especially applicable in the evaporation or dehydration of solutions of alkali metal hydroxides and particularly so 10 in those cases in which such hydroxides are prepared by electrolysis of an aqueous solution of an alkali metal salt with simultaneous evolution of hydrogen as a by-product.

It heretofore has been proposed to dehydrate electrolytically produced aqueous solutions of alkali metal hydroxide, e. g., sodium hydroxide, by first subjecting the cell liquor to evaporation in multiple effect evaporators, with removal of salt as the evaporation progresses, the said treatment being continued until the intermediate product represents about a 50% solution of the hydroxide, and then transferring the so-obtained 50% solution to a large open evaporating pot heated by a coal fire, oil blast, or the like, in which pot the solution is heated at atmospheric pressure either to dehydration or to a concentration higher than 50%, the gaseous or 20 vaporous products of evaporation being conducted by means of a hood from the pot to a point removed therefrom. The efficiency of heat transfer in this commonly employed method is known to be very low and, inasmuch as the surface for evaporation is limited, the method is a very slow one. Furthermore, contamination of the evaporated products with the products of combustion of the fuel employed, with formation of carbonates of the metals, is practically unavoidable. So 30 expensive and inefficient is this commonly employed method that investigators have proposed further evaporating partially evaporated, e. g., 50%, solutions of alkali metal hydroxides in closed jacketed vessels through the jackets of which highly heated vapors are conducted, the vaporous evaporation products being removed from the vessels by any appropriate means such as, for instance, a vapor system operated at subatmospheric pressure. While such method may result in

relatively very speedy dehydration of the solutions and an increased efficiency, the complicated special apparatus therefor makes the method expensive.

An object of the present invention is the 55 provision of a simple yet highly economical process for evaporating or dehydrating solutions of metallic hydroxides, which method may be practiced with the use of comparatively simple and inexpensive evaporation 60 equipment. Among other objects thereof is the provision of a process for evaporating or dehydrating solutions of metallic hydroxides which is not only very rapid but also effects avoidance of contamination of the evaporated 65 product.

These, and other, objects of invention are found to be attained by exposing the alkali metal hydroxide solution to be evaporated, preferably in thin layers or in finely divided 70 form or in any other form providing relatively large layers of the solution, directly in contact with burning hydrogen. That is to say, the invention resides in the evaporation of aqueous solutions of alkali metal hydroxides or their equivalents by direct contact combustion of hydrogen. High evaporation efficiency is attained thereby and, since the products of the combustion are steam and nitrogen, there is thereby eliminated any 75 possibility of contaminating the evaporated product with the combustion products. Obviously, this process finds particular applicability in the evaporation or dehydration of alkali metal hydroxide solutions obtained 80 by the electrolysis of solutions of alkali metal salts with simultaneous evolution of hydrogen, in that by the process forming the basis of the present invention there is provided an 85 economically important outlet for the by-product hydrogen.

In this connection, it is to be noted that in the electrolytic production of, say, twenty (20) tons of caustic soda there is produced by the electrolysis approximately one thousand (1000) pounds of hydrogen which, under standard conditions, is equivalent to one hundred eighty thousand (180,000) cubic feet of hydrogen. Assuming the usual heat value of 280 B. t. u. per cubic foot for the 95 100

hydrogen, there is available from this amount of hydrogen approximately fifty million four hundred thousand (50,400,000) B. t. u.'s of heat by the complete combustion of the said hydrogen. The 50% caustic soda solution which may be obtained by the evaporation of the cell liquor from the aforesaid electrolysis (the salt being removed during evaporation to 50% strength) contains approximately twenty (20) tons of water which, by standard calculation, requires approximately forty million (40,000,000) B. t. u.'s of heat for its evaporation. It will be seen, therefore, that upon a theoretical basis the by-product hydrogen is more than sufficient to supply the heat necessary for the complete evaporation of the water present in the 50% solution obtained from the cell liquor.

The process forming the basis of the present invention makes possible, and desirable, the utilization of the heat contained in the products of combustion of the hydrogen in any suitable heat exchanger, such, for instance, as a tubular boiler for the generation of steam for power and other purposes, the nitrogen in the gas either being allowed to escape or being employed for some useful purpose.

While it is not the intention of this application to restrict the working of the above-described process to the use of any particular apparatus, the method being adapted to be carried out in any one of a number of types of existing apparatus used in chemical industries, it has been found to be preferable to inject the partially concentrated solution (e. g., 50% solution) of the alkali metal hydroxide in finely divided form, e. g., as a spray, into a closed space into which the hydrogen and a gaseous supporter of its combustion are caused to pass and there burn, which closed space is provided with suitable means for removing the dehydrated product and means for conducting away the gaseous products of combustion and the water evaporated from the solution, the latter means preferably including a heat exchanger. The heat of combustion of the hydrogen evaporates the water from the stream of finely divided partially concentrated solution, the resulting dehydrated, or substantially dehydrated, caustic soda dropping to the bottom of the closed space and being removed therefrom in any suitable manner as occasion requires, and the combustion products and vaporized solvent passing out of the space. Such apparatus is already known: see Liddell, "Handbook of Chemical Engineering" (1922), pages 389 and 390, and therefore forms no part of the present invention.

As will be apparent from the foregoing, while it is not essential to the working of the broad invention to use as the hydrogen fuel for the dehydration the by-product hydrogen from electrolytic cells, and while it is

not essential that any of the heat contained in the combustion gases be saved, the best economic working of the invention includes both of these features.

It is to be understood that the present invention is not restricted to complete dehydration of the hydroxide, or to the use of a hydroxide solution of any specific strength or concentration, these being variables determined in part by the requirements in any specific practical operation of the process. Furthermore, it is not essential that the contact between the partially concentrated solution and the burning hydrogen take place in exactly the manner indicated: it may be effected by passing the burning hydrogen and/or its hot gaseous combustion products counter-currently in direct contact with a moving layer or film of the solution, or in some other suitable manner. Nor is it essential that the exposed surface of solution to be evaporated be directly contacted with the flame of burning hydrogen, it being within the scope of this invention to expose the solution either to the flame itself or to the hot gaseous combustion products thereof, these being equivalents from the standpoint of the present invention.

What I claim is:

1. Process of evaporating a solution of an alkali metal hydroxide which comprises exposing the latter directly in contact with burning hydrogen. 95
2. Process of evaporating a solution of alkali metal hydroxide which comprises exposing large surfaces of the latter directly in contact with burning hydrogen. 100
3. Process of evaporating a solution of an alkali metal hydroxide which comprises maintaining combustion of hydrogen in an atmosphere of a gaseous supporter of combustion in direct contact with a large surface of the said solution. 105
4. Process of evaporating a solution of an alkali metal hydroxide which comprises directly contacting a finely divided stream of the solution with burning hydrogen. 110
5. Process as defined in claim 1, in which the solution so exposed is a partially concentrated aqueous solution of the hydroxide. 115
6. Process as defined in claim 1, in which a previously partially concentrated solution of the hydroxide is so dehydrated.
7. Process as defined in claim 1, in which the hydroxide is caustic soda. 120

In testimony whereof, I affix my signature.

CLARENCE E. MILLER.
